CLAIM

I claim the ornamental design for the dog house dryer, as shown and described.

DESCRIPTION

FIG. 1 is a perspective view of the dog house dryer from the right front side showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view from the right front side thereof, the broken lines showing accessories are for illustrative purposes only and form no part of the claimed design.

The broken lines in FIGS. 3, 4, 5 and 6 are for illustrative purposes only and form no part of the claimed design.
